UNITED STATES PATENT OFFICE.

VINCENT BENDIX, OF CHICAGO, ILLINOIS, ASSIGNOR TO BENDIX BRAKE COMPANY,
OF CHICAGO, ILLINOIS, A CORPORATION OF ILLINOIS.

REINFORCED BRAKE SHOE.

Application filed June 7, 1926. Serial No. 114,354.

This invention relates to brakes and is illustrated as embodied in an arcuate and substantially rigid shoe for an internal expanding brake. An object of the invention is to manufacture in an inexpensive manner a very strong and rigid shoe, preferably by welding an arcuate stiffening member directly to the inner face of a cylindrical part or band to form a shoe of T-section. In one desirable arrangement, the shoe is strengthened by striking integral tongues inwardly from the cylindrical band to engage the sides of the stiffening member to which they may be welded or riveted or otherwise secured.

Another feature of the invention relates to forming a pair of projecting arms at one end of the shoe to straddle an end of an adjacent shoe, by deflecting the stiffening member to one side of the center of the shoe and continuing it beyond the shoe to form one of the arms and providing a separate and shorter stiffening member forming the other arm and which terminates at its front end at the angle in the first stiffening member formed by the above-described deflection.

Other objects and features of the invention, including various novel and desirable particular constructions, will be apparent from the following description of one illustrative embodiment shown in the accompanying drawing, in which:

Figure 1 is a side elevation of the novel shoe described above;

Figure 2 is an inside plan view of the shoe, looking upwardly toward Figure 1; and

Figure 3 is a section through the shoe on the line 3-3 of Figure 1.

In the form selected for illustration, the shoe comprises an outer cylindrical part or band 10, to which may be riveted or secured in any desired manner a brake lining 12. This outer cylindrical part is reenforced by a stiffening web formed by a separate arcuate stiffening member 14 engaging along its outer edge the inner face of part 10 and welded thereto along its outer edge. I prefer to punch tongues 16 inwardly from part 10 into radial positions where they engage the sides of the stiffening member 14 to which they may be welded. If desired, they may also be secured to the stiffening member 14 by fastenings such as rivets 18. A hard-

ened cam plate 20 is shown welded directly to the end of the stiffening cam 14.

At the anchored end of the shoe, the stiffening member 14 is deflected at 22 to one side of the center of the shoe and then continued as an anchoring arm 24 projecting beyond the end of the outer part 10 and offset within the curve 26 of the shoe to clear the end of the friction part of an adjacent shoe. In order to form a pair of such arms, I provide a separate stiffening member 28 forming the other arm and deflected at 30 toward the center of the shoe and at its forward end 32 engaging the part of stiffening member 14 at the angle formed by the deflected part 22. The separate stiffening member 28 may be welded at its outer edge to the part 10 and may be welded at its forward end to the stiffening member 14, and, if desired, it may be engaged by and secured to some of the tongues 16. The spaced arms 24 and 28 are provided with openings 34 to be pivoted upon a suitable anchor and with relatively large openings 36 to provide ample clearance for the anchor of an adjacent shoe straddled at its end by the arms 24 and 28. This overlapping relationship of the two shoes, and the passage of the anchor of the adjacent shoe through an opening such as opening 36, are fully described in Patent No. 1,567,716, granted Bendix Brake Company December 29, 1925, on application of A. Y. Dodge. This patent also describes a post for a shoe-positioning member which may pass through an opening 38 formed in the stiffening member 14.

While one illustrative embodiment of the invention has been described in detail, it is not my intention to limit its scope to that particular embodiment, or otherwise than by the terms of the appended claims.

I claim:

1. A brake shoe comprising, in combination, an outer cylindrical member substantially rectangular in cross section, and an arcuate stiffening member having its outer edge directly seated against and welded to the inner face of the outer member, the two members forming a T-section shoe.

2. A brake shoe comprising, in combination, an outer cylindrical member substantially rectangular in cross section, and an arcuate stiffening member having its outer edge seated against and welded to the inner face of the outer member, the two members

forming a T-section shoe, the stiffening member being projected beyond the end of the outer member to form an anchoring arm for the shoe.

5 3. A brake shoe comprising, in combination, an outer cylindrical member substantially rectangular in cross section, and an arcuate stiffening member engaging and welded to the inner face of the outer member, the two members forming a T-section shoe, the stiffening member being projected beyond the end of the outer member to form an anchoring arm for the shoe, the part of 10 the stiffening member forming the anchoring arm being at one side of the center of the shoe, to overlap the end of an adjacent shoe.

4. A brake shoe comprising, in combination, an outer cylindrical member substantially rectangular in cross section, and an arcuate stiffening member engaging and welded to the inner face of the outer member, the two members forming a T-section shoe, the stiffening member being deflected 25 to one side of the center of the shoe near one end of the outer member and then continued beyond the outer member to form a projecting arm, together with a separate stiffening member secured at one end to the first stiffening member where it is deflected and thence deflected in the opposite direction from the center of the shoe and continued beyond the outer member as a projecting arm spaced from the first arm.

35 5. A brake shoe comprising, in combination, an outer cylindrical member substantially rectangular in cross section, and an arcuate stiffening member engaging and welded to the inner face of the outer member 40 along its outer edge, the two members forming a T-section shoe, the stiffening member being deflected to one side of the center of the shoe near one end of the outer member and then continued beyond the outer member to form a projecting arm, together with a separate stiffening member secured at one end to the first stiffening member where it is deflected and thence deflected in the opposite direction from the center of the shoe 45 and continued beyond the outer member as a projecting arm spaced from the first arm, the outer member bridging across the inner ends of said projecting arms to reinforce them.

55 6. A brake shoe comprising, in combina-

tion, an outer cylindrical member, and a separate arcuate stiffening member engaging at its outer edge the inner face of the outer member and near one end of the shoe deflected to one side of the center of the shoe 60 and then continued beyond the outer member to form a projecting arm, together with a separate stiffening member terminating at one end adjacent the first stiffening member where it is deflected, and thence deflected in the opposite direction from the center of the shoe and continued beyond the outer member as a second projecting arm spaced from the first arm.

7. A brake shoe comprising, in combination, an outer cylindrical member, and a separate arcuate stiffening member engaging at its outer edge the inner face of the outer member and near one end of the shoe 65 deflected to one side of the center of the shoe 70 and then continued beyond the outer member to form a projecting arm, together with a separate stiffening member terminating at one end adjacent the first stiffening member where it is deflected, and thence deflected in the opposite direction from the center of the shoe 75 and continued beyond the outer member as a second projecting arm spaced from the first arm, the outer member bridging across the inner ends of said projecting arms to reinforce them.

8. A brake shoe comprising, in combination, an outer cylindrical member having tongues struck integrally therefrom and projecting inwardly, and a separate radial 80 stiffening member engaging the inner face of the cylindrical member and secured to said tongues.

9. A brake shoe comprising, in combination, an outer cylindrical member having 95 integral tongues projecting therefrom, and a separate radial stiffening member engaging the face of the cylindrical member and secured to said tongues.

10. A brake shoe comprising, in combination, an outer cylindrical member having 100 pairs of integral tongues projecting from its inner face, and a separate radial stiffening member engaging with its outer edge the inner face of the cylindrical member and 105 arranged between said pairs of tongues.

In testimony whereof, I have hereunto signed my name.

VINCENT BENDIX.
